TOOL BAG FOR MOUNTING ON THE GAS TANKS OF OUTBOARD MOTORS

Harold F. Dague, 1424 Deauville Place,
Costa Mesa, Calif. 92626

Filed Nov. 24, 1972, Ser. No. 309,518

Term of patent 14 years

Int. Cl. D3—01

U.S. Cl. D9—259

FIG. 1 is an isometric view of a first embodiment of the tool bag for mounting on the gas tanks of outboard motors, showing my new design;

FIG. 2 is a top plan view of such first embodiment;

FIG. 3 is another isometric view showing the tool bag;

FIG. 4 is an isometric view corresponding to FIG. 1 but showing a second embodiment of the tool bag;

FIG. 5 is a top plan view corresponding to FIG. 2 but showing such second embodiment;

FIG. 6 is an isometric view corresponding to FIG. 3 but showing such second embodiment;

FIG. 7 is an isometric view corresponding to FIG. 1 but showing a third embodiment of the tool bag;

FIG. 8 is a top plan view corresponding to FIG. 2 but showing such third embodiment;

FIG. 9 is an isometric view corresponding to FIG. 3 but showing such third embodiment.

The exterior side surface not shown in each of FIGS. 3, 6 and 9 is identical to the exterior side surface shown therein. The tool bag is, in each instance, shown as mounted on a gas tank, which is drawn in dashed lines.

I claim:

The ornamental design for a tool bag for mounting on the gas tanks of outboard motors, substantially as shown and described.
